(57) **CLAIM**

The ornamental design for a transportation unit for placing equipment on the sea floor, as shown and described.

DESCRIPTION

FIG. 1 is a bottom perspective view of a transportation unit for placing equipment on the sea floor as shown in the deployed position.

FIG. 2 is a top perspective view of the transportation unit for placing equipment on the sea floor as shown in FIG. 1 in the deployed position.

FIG. 3 is a perspective view of the right side and bottom end of the transportation unit for placing equipment on the sea floor as shown in the retracted position.

FIG. 4 is a perspective view of the left side and bottom end of the transportation unit for placing equipment on the sea floor as shown in the retracted position; and,

FIG. 5 is a top view of the transportation unit for placing equipment on the sea floor as shown in the deployed position as in FIGS. 1 and 2.
